Attorney, Agent, or Firm—Pearson & Pearson*[57] **CLAIM**

The ornamental design for the pair of brackets, as shown and described.

DESCRIPTION

FIG. 1 is a front side elevational view of the pair of brackets; FIG. 2 is a front perspective view of the pair of brackets showing the primary unit of my new design; FIG. 3 is a front perspective view of the pair of brackets showing the secondary unit of my new design; FIG. 4 is a front elevational view of the primary unit of the FIG. 2 pair of brackets thereof; FIG. 5 is a front elevational view of the secondary unit of the FIG. 3 pair of brackets thereof; FIG. 6 is a rear elevational view of the secondary unit of the FIG. 2 pair of brackets thereof; FIG. 7 is a rear elevational view of the secondary unit of the FIG. 3 pair of brackets thereof; FIG. 8 is a right and left side view of each unit of the FIG. 2 pair of brackets thereof; FIG. 9 is a right side front and rear view of the secondary unit shown in the FIG. 3 pair of brackets thereof; FIG. 10 is a left side view of the secondary unit of the pair of brackets thereof; and, FIG. 11 is a bottom plan view with the top plan view being identical of each unit in FIG. 2 and FIG. 3 of the pair of brackets thereof.

The broken line showing of a fragmented rod is for illustrative purposes only and forms no part of the claimed design.

The units of the claimed design are shown detached for clarity of illustration.
